UNITED STATES PATENT OFFICE.

JESSE D. LYON, OF CINCINNATI, OHIO.

EMBOSSING DEVICE.

Application filed October 6, 1922. Serial No. 592,715.

To all whom it may concern:

Be it known that I, JESSE D. LYON, a citizen of the United States of America, and a resident of Cincinnati, in the county of 5 Hamilton and State of Ohio, have invented a new and useful Improvement in Embossing Devices, of which the following is a specification.

An object of my invention is to provide 10 an improved embossing device of the class used for embossing stationery and the like.

Another object of my invention is to provide a device of this kind wherein the dies will register accurately thruout their entire 15 co-operating faces or areas.

Another object of my invention is to provide a relative compensating action for the die members whereby to avoid the objections heretofore met in devices of this kind where- 20 in the moving die operated about a fixed pivot.

Another object of my invention is to provide a simplified die actuating mechanism.

Another object of my invention is to provide 25 a simple and compact device of this type, having a minimum of movable parts, and which movable parts are simple in construction and in their co-operation.

Another object of my invention is to provide 30 a device of this type which may be readily assembled.

Another object of my invention is to provide a device which is capable of minute adjustment whereby to effect accurate regis- 35 tration of the die blocks.

These and other objects are attained by means described herein and disclosed in the accompanying drawing, in which:

Fig. 1 is a plan view of a device embody- 40 ing my invention.

Fig. 2 is a sectional view on line 2—2 of Fig. 1.

Fig. 3 is a sectional view on line 3—3 of Fig. 1.

Fig. 4 is an enlarged sectional view on line 4—4 of Fig. 2.

The base 6 is preferably long and narrow and has a transverse horizontal slot 7 formed in its head 8. A seat 9 is formed upon the 50 head 8 and extends forwardly from the vertical wall 10 which extends upon both sides of the slot 7. A lower die block 11 is mounted upon the seat 9 by means of screws 120.

The bores thru which the screws 120 ex- 55 tend are slightly larger than the shanks of

the screws, thereby permitting adjustment of the lower die block upon its seat 9. The upper portion of the head projects forwardly from the vertical wall 10 and overhangs and is substantially co-extensive with 60 the seat 9, whereby to form a lip 12. The underface 13 of the lip is spaced from the seat 9 at a distance sufficient to permit insertion in the space there-between of the lower die block 11, the upper die block 14, 65 the dies 15 and 16 carried by the die blocks, and the material which is to be embossed. The upper die block 14 is mounted on the forward end of a floating bar 17 extending longitudinally of the device. Any suitable 70 means such as screws 18, may be employed to mount the upper die block upon the bar 17. The base has a central depression 19 within which is contained a spring 20 the upper end of which extends into a 75 cap 21 engaging the bar 17. To the rear of the depression 17 is formed second or rear depression 22 within which is contained a spring 23, one end of which engages the plate 28 extending from the base and the 80 other end of which is secured to the bar 17 by any suitable means such as the screw 26. The rear end of the bar 17 is contained between the plate 28 and a plate 29 carried by the screw 30. The screw 30 carries a collar 85 31, the collar spacing the plates 28 and 29, and serving as an abutment for the rear end of the bar 17. The rear end of the bar is arcuate in form, the radius of such arc being determined by the distance between the 90 forward lower edge of the die 16 and the collar 31. The bar 17 is disposed in a way 95 34 extending longitudinally of the base. The walls of the way 34 and the bar bear a relation such that lateral play of the bar is precluded.

The lip 12 carries upwardly extending ears 41 and 42 revolvably supporting the shaft 43. A hand lever 44 is pivotally mounted on the shaft 43 and extends rearwardly from and beyond a way 45 formed between the ears. The forward end of the hand lever has a slot 46 formed in it whereby downwardly projecting lugs 47 and 48 are provided between which lugs is disposed a triangular block 49 adapted to engage the forward end of the floating bar 17. The block 49 is revolvably supported on a suitable shaft 50 carried by the lugs. The rear end of the hand lever is enlarged and 110

is hollow as shown at 52 and serves as a covering or casing for the rear end of the base. The block 49 has two faces, 51 and 55 that may be caused to assume positions over the bar 17 by turning the block about the pivot 70. The face 51 may engage the bar and pressure is transmitted from the hand lever thru the face 51 to the bar. A screw 71 carried by the lever serves to space the bar 10 from the pivot 70 when the face 55 is adjacent the bar.

The die blocks 11 and 14 each have a transverse flange 57 which form the forward edge of a way 58 extending transversely of the device, in which way the dies 15 and 16 are removably mounted. The die blocks are provided with registering pins or lugs 59 which extend rearwardly from the flanges 57 to a very short distance. The pins carried by the upper and lower die blocks are aligned. The rear edges 60 of the die blocks have notches or grooves 61 formed in them. Springs 62 have their opposite ends mounted upon the rear edges 60 of the blocks and 25 have a central distorted portion 63 which enters the notch 61 and has formed on it a lug or ridge 64, the ridges extending toward the flange 57. One end of the spring 62 is fixedly secured upon the block as shown 30 at 65, and the other end is slidably retained upon the block as shown at 66. The sliding engagement effected at 66 may be accomplished in any manner such as by providing the spring with an elongated slot 67 thru 35 which the screw 68 may pass. The head of the screw 68 is wider than is the groove 67. The ridges 64 of the lower and upper die blocks preclude vertical displacement of the dies. The dies 15 and 16 are adapted to be 40 slid into the way 58, and one each is adapted to be retained by the upper and lower die blocks. At the time the dies are prepared for mounting upon the die blocks, the dies are placed in such relation to one another 45 that the inscription upon the male die will be lodged in the matrix on the female die. The dies are retained in this relation by any suitable means whereupon the dies are notched or provided with grooves adapted 50 to accommodate the pins 59 and by the lugs or ridges 64. From the foregoing it is readily apparent that when the dies are then mounted upon their respective die blocks, the male and female dies will accurately 55 coincide and register. It will also be apparent that various dies may be interchangeably employed with the device, and that accurate registering with the male and female dies will at all times be attained with certainty 60 and with mechanical precision. The die may also be reversed. The plate 29 is provided along its side edges, with downwardly projecting flanges 290, whereby to provide a way for the rear end of the floating bar, the 65 flanges precluding lateral movement of the

rear end of the bar, and permitting vertical movement of the rear end of the floating bar.

The operation of my device is as follows:

The adjustment of the lower die block on the base permits accurate and fine transverse and longitudinal adjustment of the lower die block in relation to the upper die block. Assuming that the parts are in the relation shown in Fig. 3, and that a sheet of paper 75 has been inserted between the dies 15 and 16, the sheet may be embossed by applying pressure upon the free or rear end of the hand lever. Downward pressure on the rear end of the hand lever moves the hand lever 80 about its pivotal mounting on the shaft 43, wherefore the block 49 depresses the forward end of the floating bar 17 against the yielding action of the spring 20. The spring 23 together with the floating suspension of the 85 shaft 17 permits the upper die block and the die carried thereby, to be moved toward the lower die block in such a manner that the forward edges of the dies will first be brought into engagement. The forward 90 edges of the dies then function as a pivotal mounting about which the rear portions of the die moves. Continued movement of the hand lever brings the rear ends of the dies 95 into embossing action upon the sheet of paper. When the dies are in their operative positions upon the paper, it will be found that the rear end of the floating bar 19 will assume approximately the relation to the head of the screw 30 as is shown in Fig. 2. 100 This vertical movement of the rear end of the floating bar 17 is possible because of the sliding engagement of the collar 31 upon the rear end of the bar, the spring 23 retaining the bar upon and in engagement 105 with the collar 31.

What I claim is:

1. In a device of the class described the combination of a fixed die, a movable die, means yieldingly resisting movement of the 110 movable die toward the fixed die, an end abutment for the movable die slidably engaging the movable die, and means yieldingly retaining the movable die in engagement upon the end abutment.

2. In a device of the class described the combination of a fixed die, a movable die, means yieldingly resisting movement of the 115 movable die toward the fixed die, an end abutment for the movable die slidably engaging the movable die, means yieldingly retaining the movable die in engagement upon the end abutment, and means to bring the movable die into cooperative relationship on the fixed die.

3. In a device of the class described the combination of a base, a die carried by the base, a floating bar extending longitudinally of the base capable of movement vertically of the base, a die carried by the bar adapted 130

to cooperate with the die carried by the base, and means carried by the base for actuating the bar whereby to bring the die carried by the bar into cooperative relationship 5 with the die carried by the base.

4. In a device of the class described the combination of a base, a die carried by the base, a bar extending longitudinally of the base, a spring carried by the base yieldingly resisting movement of the bar toward the base, a die carried by the bar over-hanging the die carried by the base, a bearing carried by the base to preclude displacement of the bar in relation to the base, permitting movement 10 of the bar vertically in relation to the base and slidably engaging the bar, means yieldingly retaining the bar in engagement upon the bearing, and a lever adapted to move the bar and the die carried thereby in 15 relation to the die carried by the base.

5. In a device of the class described the combination of an elongated base, having a slot extending longitudinally thereof, a die carried by the base at one end thereof and below the slot, a bearing carried by the base at its other end, a bar contained within the slot in the base extending longitudinally of the base and having its ends disposed in proximity to the die and the bearing, the 20 end of the bar adjacent the bearing slidably engaging the bearing, a die carried by the other end of the bar, a spring yieldingly resisting movement of the bar toward the die carried by the base, a spring yieldingly retaining the bar in sliding engagement upon the bearing, and a lever adapted to move the bar toward the first mentioned die. 25

6. In a device of the class described the combination of an elongated base, having a slot extending longitudinally thereof, a die carried by the base at one end thereof and below the slot, a bearing carried by the base at its other end, a bar contained within the slot in the base extending longitudinally of the base and having its ends disposed in proximity to the die and the bearing, the end of the bar adjacent the bearing slidably engaging the bearing, a die carried by the other end 30 of the bar, a spring yieldingly resisting movement of the bar toward the die carried by the base, a spring yieldingly retaining the bar in sliding engagement upon the bearing, a lever pivotally mounted on the base, and a block carried by the lever engaging the bar above the die carried thereby. 35

7. In a device of the class described the combination of an elongated base, having a slot extending longitudinally thereof, a die carried by the base at one end thereof and below the slot, a bearing carried by the base at its other end, a bar contained within the slot in the base extending longitudinally of the base and having its ends dis-

posed in proximity to the die and the bearing, the end of the bar adjacent the bearing slidably engaging the bearing, a die carried by the other end of the bar, a spring yieldingly resisting movement of the bar toward the die carried by the base, a spring yieldingly retaining the bar in sliding engagement upon the bearing, a lever carried by the base, a block carried by the lever adapted to move the bar and the die carried thereby toward the die carried by the base, and means carried by the lever to render the block inoperative on the bar. 65 70 75

8. As a new article of manufacture a die block having an upwardly extending flange along one of its sides and having a notch 80 formed in its opposite side, a spring carried by the second mentioned side of the block extending into the notch and above the die block whereby a way is formed intermediate the spring and the flange, and means carried by the block extending into the way adapted to engage a die, the spring being adapted to yieldingly retain a die in engagement upon the last mentioned means. 85

9. As a new article of manufacture a die block having an upwardly extending flange along one of its sides and having a notch in its opposite side, a spring having one of its ends secured upon the second mentioned side of the block, extending into the notch in the block, and having its other end slidably secured upon the block, the spring and the flange providing between them a way extending over the block, the spring being adapted to yieldingly resist movement of a die through the way, and means carried by the block adapted to engage a die in the way and to preclude lateral displacement of the die. 95 100

10. A device of the class described the combination of a movable and a fixed die block, the die blocks having registering ways, means associated with the die blocks for yieldingly retaining die elements in the respective ways of the die blocks, and aligned means carried by the die blocks for positioning dies in the ways. 105 110

11. In a device of the class described the combination of a fixed die block, a movable die block, the die blocks being provided with registering ways adapted to receive complementary die members provided with aligned slots in their side edges, the die blocks being provided with aligned means adapted to extend into the slots formed in dies of the class described, and means associated with the die blocks yieldingly resisting movement of a die through the way of its respective die block. 115 120

In testimony whereof, I have hereunto subscribed my name this 2nd day of October, 1922. 125

JESSE D. LYON.
